UNITED STATES PATENT OFFICE.

HERMAN A. POPPENHUSEN, OF HAMMOND, INDIANA, AND ARTHUR P. STRONG, OF CHICAGO, ILLINOIS, ASSIGNEES TO GREEN ENGINEERING COMPANY, OF EAST CHICAGO, INDIANA, A CORPORATION OF ILLINOIS.

FIRE ARCH.

Application filed May 8, 1922. Serial No. 559,143.

To all whom it may concern:

Be it known that we, HERMAN A. POPPENHUSEN and ARTHUR P. STRONG, citizens of the United States, residing, respectively, at 5 Hammond, in the county of Lake and State of Indiana, and Chicago, in the county of Cook and State of Illinois, have invented new and useful Improvements in Fire Arches, of which the following is a specification.

This invention relates to fire-arches for furnaces, and more particularly to fire-arches made of rows of tiles suspended from metal members in the upper structure of the 15 arch.

One object of our invention is to suspend the tiles from said members by I-beams and plates, the latter extending between the I-beams and over the joints between the tiles 20 to prevent cold air being drawn down into the combustion chamber through the spaces between the tiles.

Another object of our invention is to have the I-beams which support the tiles 25 suspended from the plates and to provide sufficient clearance between the parts that the tiles and I-beams may expand and contract laterally relatively to each other under the varying temperatures to which the 30 arch is subjected without disturbing the alignment of the plates and their connections with said members nor cause the tiles to exert such undue pressure against each other on expansion that the tiles will be 35 cracked or chipped or otherwise be injured under expansion.

A further object of our invention is to have the plates engage the I-beams in such manner that the joints between said parts 40 will at all times be closed to the downward passage of cold air between them no matter to what extent the structure expands under the maximum degree of heat.

The invention consists further in the matters hereinafter described and more particularly set forth in the appended claims.

In the accompanying drawings—

Fig. 1 is a longitudinal vertical sectional view taken through a fire-arch constructed 50 in accordance with our invention;

Fig. 2 is an enlarged transverse vertical sectional view taken on line 2—2 of Fig. 1;

Fig. 3 is a longitudinal vertical sectional view taken on line 3—3 of Fig. 2;

Fig. 4 is a perspective view of one of the 55 I-beam supporting plates; and

Fig. 5 is a plan view of a detail of construction to be hereinafter described.

The fire-arch shown in the drawings comprises a plurality of tiles 1, 1 arranged in 60 longitudinal rows extending at an inclination upward and inward from the front wall of the furnace setting, as usual in structures of this general character. As illustrated in Figs. 1 and 3, the tiles 1 in each longitudinal row rest against each other along their engaging front and rear faces. The tiles 1 in adjacent longitudinal rows have substantially sidewise contact with each other, as shown in Fig. 2. In cross-section, the tiles 70 1 are shaped substantially as shown in Fig. 2, thus providing the tiles with interfitting projections and recesses 2, 3, respectively, along their side faces to provide baffles to the passage of heat upward and cold air 75 downward between the sides of the tiles.

The upper structure for the arch includes a plurality of vertically arranged metal channel members 4, 4 located above the tiles 1, 1 and extending transversely across the 80 arch between and supported by the side walls (not shown) of the furnace setting. The members 4, 4 are spaced apart laterally and are maintained in that relation by any suitable means. Extending transversely of 85 the members 4, 4 and below them are a plurality of laterally spaced I-beams 5, 5, one for each longitudinal row of tiles 1, 1, as shown in Fig. 2. Each tile 1 is provided between its side faces with an upwardly 90 opening recess or groove 6 to receive the lower flange or web 7 of the associated I-beam 5. The recess 6 in each tile is shaped as shown in the drawings to provide shoulders 8, 8 to rest on the lower flange or web 95 7 of the I-beam 5 between them. This suspends the tiles from the I-beams.

The I-beams 5 project above the tops of the tiles, and for suspending them from the transverse members 4, 4, we provide a plu-

rality of relatively flat plates 9, 9 having upwardly extending side flanges 10, 10 engaging under the upper flanges or heads 11 of the I-beams 5, as shown. Each plate 9 is 5 provided with an upwardly projecting rib or web 12 extending transversely across it, and said web has elongated bolt holes 13, 13 adjacent the ends thereof. These receive bolts 14, 14 for connecting the plates 9 with 10 suspending plates 15, which in turn are secured to the transverse members 4 by bolts 16 extending through elongated bolt holes 17 in said suspending plates. The bolts 14 extend through elongated bolt holes 18 in 15 said plates 15, as shown.

By the construction shown and described, the I-beams 5, 5 suspend the tiles 1, 1 from the cross-members 4 through the plates 9 and 15, respectively. The plates 9 extending between the I-beams 5, 5 cover the joints between the tiles, not only in each row but in the adjacent rows, and thus prevent cold air being drawn down into the combustion chamber of the furnace through the spaces 20 between the tiles. Moreover, the upright flanges 10, 10 at the sides of the plates 9 engaging under the heads 11, 11 of the I-beams prevent the downward passage of cold air 25 between such parts. The plates 9 between the I-beams are also arranged in rows, and 30 each plate has an offset end 19 overlapping the straight end of the adjacent plate to provide air seals between the meeting ends of the plates, as shown in Figs. 1 and 3.

As shown in Fig. 2, spaces 5^a are provided between the plates 9 and the I-beams 5. This presents the clearance required for the lateral expansion and contraction of the I-beams relatively to the plates 9, which are 35 fixed to the cross-members 4 against such movement. By the recesses 6 the tiles may 40 expand and contract laterally into and out of sidewise contact with each other and the spaces 5^a enable movement of the I-beams 45 under expansion of the tiles, thus relieving the latter of undue pressure when in contact and avoiding cracking and chipping of the tiles.

The plates 9, 9 being secured to the transverse members 4, 4, through the use of elongated bolt holes, as shown, enables the I-beams 5, 5 to be spaced the proper distance for centering the rows of tiles when setting up or installing the arch structure, and compensating for the degree of expansion of the parts under heat.

The upward and inward inclination of the arch makes the plates 9 take a like angle. The webs 12 on said plates being substantially at right-angles thereto, as a result, are not in true vertical planes with the cross-members 4, but are at angles thereto, as shown in Figs. 1 and 2. To meet this condition the plates 15 are formed to have vertical upper sections to fit against the cross-

members 4 and forwardly inclined lower sections to fit against the webs 12.

While we have shown and described herein in detail an arch embodying the features of our invention, it is of course to be understood that the details of construction and arrangement of parts may be variously changed and modified without departing from the spirit and scope of our invention.

We claim as our invention:

1. A fire-arch, comprising an upper structure, a plurality of contacting tiles arranged in rows beneath the same, I-beams engaged with said tiles and projecting above the same, plates extending between and engaged with said I-beams above said tiles for suspending the I-beams from said plates, said plates extending over the joints between said tiles for preventing the downward passage of air between said tiles, means for preventing the passage of air between said plates and I-beams, and means for suspending said plates from said upper structure.

2. A fire-arch, comprising an upper structure, a plurality of contacting tiles arranged in rows beneath the same, I-beams engaging recesses in said tiles and projecting above the same, there being one I-beam for each row of tiles, plates extending between and engaged with said I-beams above said tiles, and means for suspending said plates from said upper structure.

3. A fire-arch, comprising an upper structure, a plurality of contacting tiles arranged in rows beneath the same, I-beams engaged with said tiles and projecting above the same, plates extending between said I-beams above said tiles, said plates having upwardly projecting flanges at said I-beams and engaging the same beneath the flanged upper ends thereof, and means for suspending said plates from said upper structure.

4. A fire-arch, comprising an upper structure, a plurality of contacting tiles arranged in rows beneath the same, I-beams engaged with said tiles and projecting above the same, plates extending between said I-beams, said plates having upwardly projecting flanges at said I-beams and engaging the same beneath the flanged upper ends thereof, the plates between the I-beams being arranged in rows and overlapping each other at their meeting ends, and means for suspending the plates from said upper structure.

5. A fire-arch, comprising an upper structure, a plurality of contacting tiles arranged in rows beneath the same, I-beams engaged with said tiles and projecting above the same, plates extending between and engaged with said I-beams above said tiles, there being sufficient clearance provided between said I-beams and plates to permit lateral movement of the I-beams with respect to said plates under the expansion and con-

traction of said I-beams and tiles, and means for fixedly connecting said plates to said upper structure.

6. A fire-arch, comprising an upper structure, a plurality of contacting tiles arranged in rows beneath the same, a plurality of rows of plates between said tiles and upper structure and fixedly secured to the latter, and means for suspending said tiles from 10 said plates.

7. A fire-arch, comprising an upper structure, a plurality of contacting tiles arranged in rows beneath the same, a plurality of rows of plates between said tiles and upper 15 structure and fixedly secured to the latter, and means for suspending said tiles from said plates, said means permitting lateral movement of said tiles relatively to each other and to said plates under expansion 20 and contraction of said tiles and relieving undue pressure on said tiles when expanding laterally into contact with each other.

8. A fire-arch, comprising an upper structure, a plurality of contacting tiles arranged 25 in rows beneath the same, a plurality of rows of plates between said tiles and upper structure and fixedly secured to the latter, and means for suspending said tiles from the side edges of said plates, there being 30 spaces there provided to allow for expansion and contraction of said means with respect to said plates.

9. A fire-arch, comprising an upper structure, a plurality of contacting tiles arranged 35 in rows beneath the same, a plurality of rows of plates between said tiles and upper structure, means for suspending said tiles from said plates, and additional plates between said first mentioned plates and said

upper structure and connected with both for 40 suspending the tile supporting plates from said upper structure.

10. A fire-arch, comprising an upper structure, a plurality of contacting tiles arranged in rows beneath the same, a plurality 45 of rows of plates between said tiles and upper structure, means for suspending said tiles from said plates, vertical plates between the tile suspending plates and said upper structure, the latter plates having 50 upwardly projecting webs, and means adjustably connecting said vertical plates with said upper structure and said webs.

11. A fire-arch, comprising vertical cross-members in its upper structure and spaced apart in an upwardly inclined direction, a plurality of contacting tiles beneath said cross-members and arranged in upwardly inclined rows extending transversely of said cross-members, a plurality of rows of plates 60 between said tiles and cross-members, means for suspending the tiles from said plates, each plate having an upwardly projecting web aligned with the adjacent cross-member and substantially parallel thereto, vertical 65 plates extending between said webs and cross-members, and means adjustably securing said vertical plates to said webs and cross-members, said vertical plates being formed to have vertical upper sections to fit 70 against said cross-members and forwardly inclined lower sections to fit against said webs.

In testimony that we claim the foregoing as our invention, we affix our signatures, this 75 1st day of May, A. D. 1922.

HERMAN A. POPPENHUSEN.
ARTHUR P. STRONG.
